Dunham, Coker, & Sage assignees of
William L. Sanderson of Troy New York
Letters Patent No 255 dated Dec 18th 1849

The schedule referred to in these Letters Patent and making part of the same
To all whom it may concern

Be it known that I
William L. Sanderson of Troy in the County
of Rensselaer and State of New York have

I

Des. 958

invented or produced a new design of parlor stove pattern, and I do hereby declare that the following is a full clear and exact description of the same, reference being had to the annexed drawings, which are a part of this specification in which fig. 1 is a view of the bottom, fig. 2, of the top, fig. 3, front; and fig. 4, a view of the end plates of the stove, fig. 5, is a vertical side view of the corn. On the respective plates I have represented the ornament in part, that which is omitted, being a repetition of the same and corresponding with that represented on the parts left blank in the drawings.

What I claim as new, and desire to secure by letters patent, is the design and configuration of an ornamental parlor stove substantially the same as described and represented in the hereto annexed drawings.
